MULTIPURPOSE TOOL OR SIMILAR DEVICE

Benno Bothe, 1508 Hiway 46 S.,
New Braunfels, Tex. 78130

Filed Aug. 1, 1969, Ser. No. 18,503

Term of patent 14 years

Int. Cl. D8—02

U.S. Cl. D8—19

FIG. 1 is a plan view of a multipurpose tool or similar device, showing my new design;

FIG. 2 is a top edge view thereof;

FIG. 3 is a bottom edge view thereof;

FIG. 4 is a right edge view thereof; and

FIG. 5 is a left edge view thereof.

The underside of the multipurpose tool or similar device is plain.

I claim:

The ornamental design for a multipurpose tool or similar device, as shown and described.
